UNITED STATES PATENT OFFICE.

CARL SATTLER AND HOWARD B. HASKINS, OF TOLEDO, OHIO, ASSIGNEES, BY MESNE ASSIGNMENTS, TO THE DURA COMPANY, OF TOLEDO, OHIO, A CORPORATION OF OHIO.

WINDOW STRUCTURE.

Application filed July 5, 1927. Serial No. 203,362.

The invention relates to window structures and refers more particularly to window structures for railway cars. One of the objects of the invention is to so construct the window structure that the windows may be raised or lowered by window regulators to open or closed positions. Another object is to provide means for effectively sealing the spaces between the windows and the frame of the car when the windows are closed to prevent the entrance of smoke, dust, moisture or the like into the car. A further object is to provide means for closing the space between a window screen when lowered and a window when opened to prevent the entrance of smoke, dust or the like into the car. With these as well as other objects in view, the invention resides in the novel features of construction as more fully hereinafter set forth.

20 In the drawings:—

Figure 1 is an interior side elevation, partly broken away, of a portion of a railway car having applied thereto a window structure embodying our invention;

25 Figures 2 and 3 are respectively cross sections on the lines 2—2 and 3—3 of Figure 1.

The vehicle to which our invention is particularly applicable is a Pullman car having a frame including the laterally spaced metallic uprights 1, the metallic sills 2 extending between these uprights and located at the bottom of the window opening, and the inner and outer top bars 3 and 4 above the window opening and extending between the uprights. 30 The car is also provided with the inner and outer panels 5 and 6, which together with the uprights form a chamber 7 above the window opening.

8 and 9 are respectively the inner and outer windows for the window opening, each being 40 in the nature of a sashless glass vertically slidable in the guides 10 which are suitably mounted upon the uprights 1 in such a manner that the spaces between the guides and the uprights are closed to prevent the entrance of smoke, dust, moisture or the like into the car. 11 is a vertically movable screen 45 slidably engaging the metallic guides 12 which are secured to the uprights 1, this screen being movable between the inner and outer windows. For raising or lowering the windows 8 and 9 to open or closed positions there are the pivotal lifter arms 13 and 14 respectively, which form parts of separate 50 window regulators so that either window may

be raised or lowered independently of the other. These lifter arms extend within the chamber 7 and have at their free ends the transverse projections 15 which may be suitably secured to the lifter arms and are engageable in the grooves formed by the retainers 16 and channels 17, the latter embracing and being secured to the upper edges of the glasses. The screen 11 is also raised and lowered and as shown in the present instance the screen is operated upon movement of the inner glass 8 as by means of cables 18 having one end connected to the top of the chamber 7 and the other end connected to the top of the screen, intermediate portions 60 of each cable passing over pulleys 19 and 20 secured respectively to the top of the inner glass 8 and the top of the chamber. The arrangement is such that upon upward movement of the inner glass the screen is lowered 65 and its rate of travel is twice that of the outer glass. As a consequence, this screen when not in use may be fully concealed within the chamber 7.

For the purpose of sealing the spaces between the upper edges of the glasses 8 and 9 and the frame of the car when these glasses are in fully lowered or closed positions so that smoke, dust and the like cannot enter the car, we have provided the cooperating resilient 80 weatherstrips 21 and 22, respectively, upon the frame and each glass. The weatherstrips 21 may be formed of rubber or the like while the weatherstrips 22 are preferably curved projections integral with and depending from 85 the channels 17. The weatherstrip 21 for the inner glass 8 is mounted in the transversely extending channel 23 of the retainer 24 which is secured to the outer side of the inner top bar 3. The weatherstrip 21 for the outer 90 glass 9 is secured in the channel 25 of the retainer 26, which has at its upper end the transverse flange 27 secured to the outer top bar 4. The lower edges of the retainers 24 and 26 and the inner top bar 3 are preferably 95 in the same horizontal plane and define the upper edge of the window opening.

For sealing the joint between the lower edges of the glasses 8 and 9 and the sill 2 when these glasses are in their fully lowered or closed positions, there are the resilient weatherstrips 28 which may be formed of rubber or the like. Each of these weatherstrips has a Y-shaped cross section and its stem 29 extends transversely of the glass at 100 105 110

its lower edge and is firmly secured thereto while its legs 30 and 31 are adapted to abut the sill at spaced points, the leg 30 extending under the glass. For securing each 5 weatherstrip 28 to its glass, there is the channel 32 embracing and secured to the lower edge of the glass and having at its outer side a return bent portion forming the flange 33, which is curved to accommodate 10 the bead at the upper edge of the stem and to grip the neck of the stem between the bead and the legs so that the weatherstrip cannot become accidentally disengaged.

To seal the space between the screen 11 15 when lowered and the outer glass 9 when raised so that smoke dust and the like cannot enter the car in the event that the inner glass 8 is also raised to open position, there is the resilient weatherstrip 34 preferably 20 secured to the upper edge of the screen and engageable with the inner side of the channel 32 upon the outer glass. The joint between the lower edge of the screen and the sill is also sealed by a resilient weather- 25 strip 35.

What we claim as our invention is:

1. The combination with a vehicle having a frame providing a window opening and a sill at the lower end of the opening, of a 20 vertically movable window for the opening, and a resilient weatherstrip secured to said window and having a plurality of legs of equal length for simultaneously engaging said sill when said window is in lowered 35. position.

2. The combination with a vehicle having a frame providing a window opening and a sill at the lower end of the opening, of a vertically movable window for the opening, 40 and a resilient Y-shaped weatherstrip having its stem secured to said window and its legs engageable with said sill.

3. The combination with a vehicle having a frame providing a window opening and a 45 sill at the lower end of the opening, of a vertically movable glass constituting a win-

dow, a channel embracing the lower edge of said glass and having a return bent portion at one of its sides and a resilient Y-shaped weatherstrip having its stem secured to said 50 clip by said return bent portion and its legs engageable with said sill when said glass is in lowered position.

4. The combination with a vehicle having a window opening, of a vertically movable 55 window, a vertically movable screen, and means upon one of said members engageable with the other when said screen is in fully lowered position and said window is in fully raised position.

5. The combination with a vehicle having a window opening, of a vertically movable window, a vertically movable screen, and means upon said screen engageable with said window, when said screen is in fully lowered position and said window is in fully 65 raised position.

6. The combination with a vehicle having a window opening, of a vertically movable window, a vertically movable screen, and a 70 weatherstrip carried by the upper end of said screen and engageable with the lower end of said window when said screen is in fully lowered position and said window is in fully raised position.

7. The combination with a vehicle having a frame providing a window opening and a sill at the lower end of the opening, of a vertically movable window for the opening, and a yieldable weatherstrip having a 80 portion secured to said window and a second portion extending from said first mentioned portion and having spaced points of contact with said sill when the window is in lowered position, the two sections of said weatherstrip being relatively movable so as to permit an efficient sealing action between the second section and said sill.

In testimony whereof we affix our signatures.

CARL SATTLER.
HOWARD B. HASKINS.
